UNITED STATES PATENT OFFICE.

CHARLES W. BREED, OF WESTERN SPRINGS, ILLINOIS.

SWITCH-STAND.

1,380,037.

Specification of Letters Patent. Patented May 31, 1921.

Application filed June 7, 1920. Serial No. 387,104.

To all whom it may concern:

Be it known that I, CHARLES W. BREED, a citizen of the United States, residing at Western Springs, in the county of Cook and 5 State of Illinois, have invented a certain new and useful Improvement in Switch-Stands, of which the following is a full, clear, concise, and exact description, reference being had to the accompanying drawings, forming a part of this specification.

My invention relates to railway switch stands and has for its principal object the provision of a switch stand embodying certain improved features of construction 15 which render the device thoroughly reliable in operation and very serviceable.

The foregoing and other objects and advantages of my improved switch stand will appear from the following detailed description, wherein—

Figure 1 is a vertical cross-section of a conventional type switch stand embodying the improvements of my invention;

Fig. 2 is a horizontal sectional detail 25 taken on line 2—2 of Fig. 1, looking in the direction indicated by the arrows; and

Fig. 3 is a vertical sectional detail taken on line 3—3 of Fig. 1, looking in the direction indicated by the arrows.

The same reference numerals designate the same parts throughout the several views.

Referring to the drawings, the reference numeral 5 designates the base member of the switch stand which comprises a preferably integral bottom plate 6 which is generally provided with holes to receive spikes to secure the stand in position. Provided at 7 and 8 in the base member 5 are bearings in which is mounted a vertical mast

40 9 to the upper end of which are secured the day signal color targets 10 and 10^a. The lower end of the mast 9 is provided with a crank 11, the free end of which carries a crank pin 12. Pivotal connected to the

45 crank 11 by the pin 12 is a connecting rod 13 which has connection with a switch in the usual manner. A bracket 14 secured to the mast 9 by a rivet 15 projects at right angles to the mast 9 over a flange 5^a provided on the top of the base member 5. The

50 free end of the bracket 14 is bifurcated and provided with bearing bosses 16—16. A housing 17, preferably formed integral with bracket 14, extends over the bifurcated portion and has a slot 17^a formed in its face. An operating lever 18 has a free end ex-

tending into the housing 17 and is pivoted to the bracket 14 by a rivet 19 which extends through the bearing bosses 16—16. A suitable eye bolt 20 secured in the free 60 end of the lever 18 extends through the slot 17^a in the housing 17 and is adapted to receive a lock 20^a to prevent unauthorized operation of the switch. Suitable notches, one of which is indicated at 21 in Fig. 1, are 65 provided in the edge of the flange 5^a to receive the lever 18, whereby the same may be locked into either of its two operative positions.

Formed integral with the base member 5 70 are comparatively heavy lugs 22—22 which project laterally from the front of the base member in spaced relation, as seen in Figs.

1 and 2. The lugs are arranged to shield the end of the crank 11 and to prevent accidental disconnection of the connecting rod 13 from the crank pin 12. A ledge 23 is conveniently provided on the base member 75

5 above the lugs 22—22 and lying on a line between the lugs so that a maintenance man 80 may mount the stand by first stepping upon either of the lugs 22 and thence upon the ledge from which he may readily reach any point on the mast and the targets, it being

understood that the mast is generally about 85 eight feet tall. The lugs 22 are cast integral with the base member as shown, and therefore there are no crevices or cracks in

which moisture can collect which causes an untimely rusting off of the lugs, as where 90 the same are riveted or otherwise secured upon the base, to which cause many serious accidents have been laid; the connecting rod

becoming disassembled from the crank.

Formed in the bottom of the base mem- 95 ber 5 is an opening 24 which, as most clearly shown in Figs. 1 and 2, is sufficiently large to permit insertion of the mast 9 through the same, the crank 11 projecting rear-

wardly as indicated in dotted lines in Fig. 100 1. Another opening 25 formed in the front wall of the base 5 extends the entire width of the same and at its upper edge lies flush with the bottom of the lugs 22—22, as seen in Fig. 1. A table 26 is provided by a web 105

extending across the bottom of the base 5 beneath the lugs 22—22, adjacent the opening 24. In assembling the switch stand, the

mast 9 is inserted into the base member until the crank 11 occupies the position shown in 110 Fig. 1, whereupon the mast is rotated through approximately 180°, so that the

crank 11 travels above the table 26. The mast is positively prevented from dropping out through the bottom of the base 5 because of the table 26. The bracket 14 is then 5 assembled on the mast 9 and the end of the connecting rod slipped over the pin 12.

That portion of the mast 9 extending from the bearing 7 to the lower end thereof is circular in cross-section and the portion 10 above the bearing 7 is square in cross-section for a purpose which will presently appear. As seen most clearly in Fig. 3, the bosses 16—16 project slightly into the housing 17 to provide shoulders 27—27. As seen 15 in Fig. 1, the shoulders 27—27 extend inwardly toward the mast 9 to the point 27^a to provide a channel for the enlarged end portion of the lever 18, whereby the lever 18 may be easily assembled in the bracket 14. 20 The free end of the lever 18 projects into the housing 17 as aforesaid and the enlarged portion 28 provides shoulders 29—29 on its opposite sides. When the lever 18 is in its inoperative position, the shoulders 29—29 25 lie above and are spaced slightly from the shoulders 27—27, as seen in Fig. 3. The hole in the boss 30 of the bracket 14 is conformed to fit the square portion of the mast 9 passing therethrough.

30 Serious accidents on railroads have very often been caused by the switch stands which, despite regular and frequent inspection, become badly rusted at certain concealed points as to permit free movement of 35 the switch points. One of the principal advantages of the switch stand of my invention is that it permits the inspector to observe at a glance whether the sand is in its usual operating condition and also in the 40 even the inspector should, through carelessness or otherwise, fail to observe the condition of the stand, the stand will in a measure still continue to give service and will at least prevent opening of the switch points 45 and thus prevent any serious accidents.

The pin 19, experience has shown, sometimes rusts off or breaks. However, when this occurs the enlarged portion 28 of the operating lever 18 serves to prevent the lever 50 from dropping off of the bracket 14 because of the shoulders 29—29 which, in such event, engage the shoulders 27—27. The lock 20^a serves to prevent unauthorized or 55 accidental operation of the switch, since the handle cannot be moved to its horizontal position. It will appear also that the switch stand is not rendered totally inoperative through such a mishap, because the lever 18 may still be turned to horizontal position 60 and the switch operated when the lock 20^a is removed.

Furthermore, in the event the rivet 15 breaks or in any other manner becomes useless, the mast 9 will drop slightly so that the 65 crank 11 will engage the table 26. The

switch may still be operated because of the square conformation of the mast 9 co-operating with the square hole in the base 30 of the bracket 14. The lugs 22—22 being formed integral with the base plate and being conformed to shed moisture from their surfaces generally last long as the base member and serve to prevent accidental disconnection of the connecting rod 13 from the pin 12, and to prevent unauthorized movement of the switch points. It will thus appear that although the various elements of the switch stand may become disconnected, the stand is not rendered inoperative. 75

While I have described the details of a 80 preferred embodiment of my invention, I in no wise limit myself to the details of construction disclosed, but cover all equivalent embodiments falling within the spirit and scope of the appended claims. 85

What I claim is:

1. A railway switch stand comprising a vertical hollow base member having openings formed in its bottom and front wall, lugs formed integral with said base member projecting laterally from said front wall over the opening therein, a mast inserted into said base member through the opening in the bottom thereof mounted in bearings in said base member and projecting vertically therefrom, a crank on said mast extending at right angles thereto and projecting through the opening in the front wall of said base member, a crank pin projecting vertically from said crank for receiving the end of a switch operating connecting rod, said pin occupying either of two operative positions beneath said lugs, a bracket secured to said mast and extending at right angles thereto, said bracket being bifurcated at its free end and having bearing bosses, a housing on said bracket into which said bosses project, and an operating lever pivoted to said bracket between said bosses, said lever having an enlarged end 90 projecting into said housing beyond said bosses. 95

2. A railway switch stand comprising a base member having openings formed therein, lugs projecting laterally from said base member, a mast inserted into said base member through an opening in the bottom thereof mounted in bearings in said base member and projecting vertically therefrom, a crank on said mast extending at right angles thereto and projecting through an opening in the wall of said base member, a crank pin projecting from said crank for receiving the end of a switch operating connecting rod, said pin occupying either of two operative positions beneath said lugs, a bracket for said mast, said bracket being bifurcated at its free end and having bearing bosses, a housing on said bracket into which said bosses project and an operating 110 115 120 125 130

lever pivoted to said bracket between said bosses, said lever having an enlarged end projecting into said housing beyond said bosses.

5 3. A railway switch stand comprising a base member having openings formed therein, lugs on said base member, a mast inserted into said base member mounted in bearings therein and projecting vertically therefrom, a crank on said mast extending at right angles thereto and projecting through an opening in the wall of said base member, a crank pin on said crank for receiving the end of a switch operating connecting rod, 10 said pin occupying positions beneath said lugs, a bracket for said mast, said bracket having bearing bosses formed thereon, a housing on said bracket into which said bosses project and an operating lever pivoted to said bracket between said bosses, said lever having an enlarged end projecting into said housing beyond said bosses.

4. In a railway switch stand, the combination of a mast, a crank on said mast for 25 operating a switch, a bracket on said mast, means for preventing relative rotation of said mast and said bracket, comprising a hole in said bracket, conformed to accommodate said mast, an operating lever for 30 said mast pivotally secured to said bracket, means for preventing disassembling of said lever from said bracket comprising an enlargement on said lever and bosses on said bracket to engage said enlargement, a base 35 member having an opening in the bottom thereof for receiving said mast, said mast upon insertion, being reversed from its operating positions, a table adjacent said opening, and said base member having an opening 40 in the wall thereof over said table for receiving said crank, said table being disposed beneath said crank.

5. In a railway switch stand, the combination of a mast, a crank for operating a 45 switch, a bracket on said mast, means for preventing relative rotation of said mast and said bracket, an operating lever for said mast pivotally secured to said bracket, means for preventing disassembling of said 50 lever from said bracket comprising an enlargement on said lever and bosses on said bracket to engage said enlargement, a base member having an opening in the bottom thereof for receiving said mast, said mast, upon insertion, being reversed from its operating 55 positions, a table adjacent said opening, and said base member having an opening in the wall thereof over said table for receiving said crank, said table being disposed 60 beneath said crank.

6. In a railway switch stand, the combination of a mast, a crank for operating a switch, a bracket on said mast, an operating lever for said mast pivotally secured to said 65 bracket, means for preventing disassembling

of said lever from said bracket comprising an enlargement on said lever and bosses on said bracket to engage said enlargement, a base member having an opening in the bottom thereof for receiving said mast, said mast, upon insertion, being reversed from its operating positions, a table adjacent said opening, and said base member having an opening in the wall thereof over said table for receiving said crank, said table being 70 disposed beneath said crank.

7. In a railway switch stand, the combination of a mast, a crank for operating a switch, a bracket on said mast, an operating lever for said mast secured to said bracket, 80 means for preventing disassembling of said lever from said bracket, a base member having an opening in the bottom thereof for receiving said mast, said mast, upon insertion, being reversed from its operating positions, 85 a table adjacent said opening, and said base member having an opening in the wall thereof over said table for receiving said crank, said table being disposed beneath said crank.

8. In a railway switch stand comprising a 90 base member, a mast, a crank on said mast and a crank pin on said crank for receiving the end of a switch operating connecting rod, the combination with said crank pin and connecting rod of comparatively heavy 95 lugs formed in spaced relation upon said base member to prevent disassembly of said connecting rod from said crank pin and to shield said crank pin when the crank is in operative position, and a ledge on said 100 base member above said lugs, said ledge and lugs forming steps whereby a maintenance man may mount the stand to gain access to all points thereon.

9. In a railway switch stand comprising 105 a base member, a switch operating mast mounted therein and extending therefrom, a bracket fixed against relative rotation on said mast and pinned thereto to prevent relative endwise movement, an operating lever 110 for said mast pivoted to said bracket, said lever having shoulders formed on the end thereof, means in said bracket for engaging said shoulders to prevent disassembly of said lever and bracket, and a table in said 115 base member to prevent said mast from dropping out of said base member.

10. In a railway switch stand comprising a base member, a switch operating mast mounted therein and extending therefrom, a 120 bracket on said mast, an operating lever for said mast pivoted to said bracket, said lever having shoulders formed on the end thereof, means in said bracket for engaging said shoulders to prevent disassembly of said 125 lever and bracket and a table in said base member to prevent said mast from dropping out of said base member.

11. In a railway switch stand comprising 130 a base member, a switch operating mast

mounted therein and extending therefrom, a bracket on said mast, an operating lever for said mast pivoted to said bracket, said lever having shoulders formed on the end thereof, 5 and means in said bracket for engaging said shoulders to prevent disassembly of said lever and bracket.

12. In a switch stand comprising a base member, a signal mast mounted therein, a 10 crank integral with said mast, a crank pin thereon, a switch operating connecting rod thereon, an operating lever connected to said

mast, and a comparatively heavy lug cast integral with said base member slightly above the bottom thereof adapted to prevent 15 disassembly of said connecting rod from said crank pin when the crank is in operative position.

In witness whereof, I hereunto subscribe my name this 27th day of May, 1920.

CHARLES W. BREED.

Witnesses:

ANDREW WINTERCORN,
J. DAVID DICKINSON.
